(57) **CLAIM**

The ornamental design for an insulator for vacuum circuit breaker, as shown and described.

DESCRIPTION

FIG. 1 is a front, top and left side perspective view of an insulator for vacuum circuit breaker, showing our new design; FIG. 2 is a front elevational view thereof; FIG. 3 is a left side elevational view thereof; FIG. 4 is a right side elevational view thereof; FIG. 5 is a top plan view thereof; FIG. 6 is a cross-sectional view thereof; taken in the direction of line 6-6 of FIG. 3; and, FIG. 7 is a cross-sectional view thereof; taken in the direction of line 7-7 of FIG. 3.
